[57] CLAIM

I claim the ornamental design for flashlight, as shown and described.

DESCRIPTION

FIG. 1 is a top/right side/rear isometric view of a first embodiment of a flashlight showing my new design having a translucent panel in the center of the top;

FIG. 2 is a front side elevational view thereof, the right, left and rear side elevational views being the same and, therefore, not shown;

FIG. 3 is a top plan view of a second embodiment thereof having a transparent panel in the center of the top to reveal a concave inner chamber with a central bulb that is disclosed, the front, right, left and rear elevational views of the second embodiment being the same as the first embodiment and, therefore, not shown; and,

FIG. 4 is a bottom view of the first embodiment thereof, the bottom view of the second embodiment being the same and, therefore, not shown.
